(57) CLAIM

The ornamental design for an oil lamp, as shown and described.

DESCRIPTION

FIG. 1 is a perspective view of our design;

FIG. 2 is a front elevation view of the embodiment of FIG. 1, the other sides and rear being the same;

FIG. 3 is a top plan view of the embodiment of FIG. 1;

FIG. 4 is a bottom plan view of the embodiment of FIG. 1;

FIG. 5 is a perspective view of a second embodiment of our design;

FIG. 6 is a front elevation view of the embodiment of FIG. 5, the other sides and rear being the same;

FIG. 7 is a top plan view of the embodiment of FIG. 5; and,

FIG. 8 is a bottom plan view of the embodiment of FIG. 5. The area inside the dashed lines of FIGS. 4, 8, forms no part of the claimed design.
